UNITED STATES PATENT OFFICE

HORACE H. RAYMOND, OF BERLIN, CONNECTICUT, ASSIGNOR TO THE STANLEY WORKS,
OF NEW BRITAIN, CONNECTICUT, A CORPORATION OF CONNECTICUT

SHELF BRACKET

Application filed June 14, 1928. Serial No. 285,240.

This invention relates to a bracket adapted to be secured to a wall and to support a shelf, or the like.

The aim of the invention is to provide a bracket of this sort which is characterized by its simplicity in construction, its economy in manufacture, and the ease and facility with which it may be secured firmly in place. A bracket constructed according to the present invention may be very cheaply made from inexpensive stock, preferably strip metal, and, although the bracket is of relatively light weight, it is strong and durable.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawing, wherein I have shown, for illustrative purposes, one of the embodiments which the present invention may take:

Figure 1 is a perspective view of my improved bracket; and

Fig. 2 is a side view of the same secured in place.

In accordance with the present illustrated disclosure of my invention, the bracket is formed from a strap or strip of metal which is bent generally into the form of a right angled triangle so as to provide a vertical leg 10, a horizontal leg or shelf-supporting portion 11, and a hypotenuse or strut-portion 12. The lower forward corner of the bracket is truncated so as to provide a short vertical length 13 between the base or leg 11 and the hypotenuse. The shelf S is supported by the base 11 and, if desired, may be secured thereto by nails 14. The strut-portion 12 prevents the shelf from falling off. Obviously, the shelf S is shown by way of example only, as the brackets may support various articles, such as rods.

The metal strip, from which the bracket

is formed, is twisted or bent through an angle of 90° at the lower end of the strut 12, so that this strut is brought into a vertical plane and at right angles to the planes of the legs 10 and 11. The upper end of the strut 12 is curled or rolled upon itself so as to form a cylindrical sleeve 15, the axis of which is at right angles to the length of the strut 12. This sleeve is inclined downwardly and rearwardly with respect to the vertical leg 10. The internal diameter of the sleeve 15 is such as to more or less snugly receive the shank of a nail 16 by means of which the bracket is adapted to be secured in place. The upper end of the leg 10 is provided with a V-shaped transversely-extending projection or corrugation so as to provide a downwardly and outwardly inclined seat 17 for the rear end of the sleeve 15. This seat portion 17 is provided with an opening 18 adapted to register with the opening through the sleeve so as to accommodate the nail 16.

The bracket may be very securely and easily secured in place by inexperienced persons by merely positioning the vertical leg 10 against a wall to which the bracket is to be secured, and then hitting the head of the nail with a hammer or other suitable tool. The sleeve 15 and the opening in the seat 17 constitute a guide for the nail as it is being driven into place. The nail is driven into the wall at such angle that the weight of the bracket will not pull the nail from place; but, on the other hand, will tend to hold it more firmly in place. After the nail 16 is driven home, another nail 20 may be driven into the wall through an opening 21 in the vertical leg 10.

It will be observed that my improved bracket may be very easily and economically manufactured from strip metal; the ends of the strip metal from which the bracket is manufactured are securely and firmly held together by the nail which secures the bracket in place; and the bracket may be easily applied by inexperienced persons.

As many changes could be made in the above construction and many apparently widely different embodiments of the invention could be made without departing from

the scope thereof, it is intended that all matter contained in the above description, or shown in the accompanying drawings, shall be interpreted as illustrative and not in a limiting sense.

5 It is also to be understood that the language used in the following claims is intended to cover all of the generic and specific features of the invention herein described and all 10 statements of the scope of the invention which, as a matter of language, might be said to fall therebetween.

15 I claim as my invention:

1. A bracket for supporting a shelf or the like and comprising a right-angled triangular member formed of a strip of metal and having a vertical wall-engaging portion, a horizontal shelf supporting portion, and an inclined strut, said wall-engaging portion 20 having adjacent its upper end a V-shaped offset, the upper leg of which is provided with an opening, the upper end of said strut being rolled to form a downwardly and rearwardly inclined sleeve, the end of said sleeve 25 being adapted to rest upon said offset; and a nail extending through said sleeve and said opening in said offset for holding said bracket in closed position and securing the same in place.

30 2. A bracket for supporting a shelf or the like and comprising a strip of metal bent into triangular form and having a vertical wall engaging portion, a horizontal shelf supporting portion extending from the lower end of 35 said wall engaging portion, and an inclined strut extending upwardly and rearwardly from the forward end of said shelf receiving portion, the ends of said strip being brought together at the top of the wall engaging portion, the upper end of said strut being rolled 40 to form a downwardly and rearwardly inclined nail receiving sleeve, said wall portion adjacent its upper end having an opening in registry with the bore through said 45 sleeve, and a nail extending through said sleeve and opening for tying the ends of the bracket together and securing said bracket in place.

HORACE H. RAYMOND.
